UNITED STATES PATENT OFFICE.

STEPHEN KOSTSZEWSKI, OF NEW YORK, N. Y., ASSIGNOR TO ROBERT FINDLAY MANUFACTURING CO., OF NEW YORK, N. Y., A CORPORATION OF NEW YORK.

DESIGN FOR A RING FOR LIGHTING-FIXTURES.

59,425.

Specification for Design.

Patented Oct. 18, 1921.

Application filed March 9, 1921. Serial No. 450,975. Term of patent 7 years.

To all whom it may concern:

Be it known that I, STEPHEN KOSTSZEWSKI, a citizen of the United States, residing at New York, in the county of New York and State of New York, have invented a new, original, and ornamental Design for a Ring for Lighting-Fixtures, of which the following is a specification, reference being had to the accompanying drawing, forming part thereof.

Figure 1 is a plan view of a ring for lighting fixtures, embodying my new design.

Fig. 2 is a side view of the same.

I claim:

The ornamental design for a ring for lighting fixtures, as shown.

STEPHEN KOSTSZEWSKI.
